UNITED STATES PATENT OFFICE.

JAMES E. CLARK, OF DETROIT, MICHIGAN, ASSIGNOR TO CONTINUOUS TRAIN CONTROL CORPORATION, OF DETROIT, MICHIGAN, A CORPORATION OF MICHIGAN.

SAFETY CIRCUIT FOR TRAIN-CONTROL SYSTEMS.

Application filed February 1, 1926. Serial No. 85,156.

This invention relates to train control systems whereby electro-magnetic waves are propagated in the rails of each block into which the track is divided and include means whereby the wave lengths are determined by the occupancy of the track ahead, which systems further comprise loop collector coil circuits on the locomotive for picking up such electro-magnetic waves and utilizing them for the purpose of permitting or obstructing the flow of current through electron tubes on the locomotives and of relays controlled by such currents to govern the operation of electro-pneumatic valves connected to the air brake systems of the locomotives.

This invention consists in a novel circuit between a current source and the filaments of the electron tubes to carry the current whereby the tubes are rendered active, so connected to the collector coils that all the coils constitute a portion of this circuit, no matter how many coils are employed, so that, should any one of the coils become broken for any reason whatever, the electron tubes immediately become inoperative and the instrumentalities controlled thereby become inactive, resulting the air-brakes operating to stop the train.

It further consists of the details of construction illustrated in the accompanying drawing and particularly pointed out in the claims.

In the accompanying drawing, Fig. 1 is a diagrammatic view of the present invention constituting a part of an automatic train control installation. Fig. 2 is a front elevation of a coil-supporting bracket.

Similar reference characters refer to like parts throughout both views.

The air brake mechanism shown by the drawing as embodying the present invention is designed to be used in connection with instrumentalities on the locomotive which are controlled by electro-magnetic waves flowing in the track rails over which the locomotive is passing, and attention is called to the Thomas E. Clark Patent Number 1,262,637, dated April 16, 1918, which shows propagating mechanism for electro-magnetic waves attached to the exit ends of the blocks into which the track is divided. Each installation is controlled by the next installation ahead and functions to propagate current of one wave length, say

8000 meters, when the conditions of the block of track pertaining to such installation are for safety or "clear", and current of another wave length, say 6000 meters, when the conditions of such block are for "danger". Any other desired means may be employed to propagate such currents under "clear" and "danger" conditions.

The track installations adapted to the present train control devices are of such power and wave lengths that only a limited length of track at the exit end of each block is energized by these installations sufficiently to affect the instrumentalities on the locomotive. These instrumentalities are not affected while passing over the remainders of the blocks.

The locomotive instrumentalities embody two collector coils 100 and 101, one for each wave length, mounted on the locomotive where they can be influenced by the lines of force of such electro-magnetic waves. These connect to two electron tubes 102 and 103 which have the usual characteristic that when negative potential accumulates in the grids, the flow of electrons from the filaments to the plates is interrupted and therefore substantially stops the flow of current in the plate circuits. These plate circuits embody relays normally energized by the flow of the current in the plate circuits.

I prefer to use a two-voltage generator 104 which may be driven in any desired manner. The common wire to this generator for both voltages is the heavy wire 105. When the coil 101 cuts lines of force of a current in the rails of say 6000 meters wave length, current flows from this coil over wire 106 to the grid of tube 103, the grid leak 107 connecting this wire with the return wire 109, the usual condenser 108 being connected into this circuit, which may be tuned to the desired wave length by the adjustable condenser 110. The heating circuit for the filament of this tube is from the generator 104 over the wire 112, resistance 113, which reduces the voltage from say 32 to 12 volts, wires 114, 115 and 116, filament of tube 102, wires 117, 109 and 118, filament of tube 103, wire 119, adjustable resistance 120 to common wire 105.

The reason for passing this current over the wires 115, 116, 109 and 118 is to cut out the current to both filaments should either of the coils 100 and 101 or the supports 110

therefor be torn from the wires 116-118 through accident. But otherwise, current flows to these filaments at all times that the generator is in operation.

5 Each of these coils 100 and 101 is preferably mounted within a shell 80 supported by a trunking or hollow bracket 81 extending down from a bolster 82 forming part of the locomotive or other vehicle on which this installation is mounted. The wires connected to these coils extend up through the brackets 81 and will be ruptured when the brackets are broken or torn from the bolster.

10 15 The receiver circuit of the coil 100 comprises the wires 122 and 123, adjustable condenser 124 and wires 125, 114 and 115. The grid condenser 126 and grid leak 127 serve to impose negative potential on the grid of tube 102. When the grid of tube 103 has sufficient negative potential to obstruct the flow in the plate circuit, insufficient current flows to the relay 128 over the common wire 105, adjustable resistance 120, wire 119, filament to plate in tube 103, and wire 132 to this relay, from which current would normally flow over wire 130, armature 128^b and wire 129 to the high voltage side of the generator.

20 25 30 But if this circuit is interrupted (as shown) because of lack of sufficient current to energize this relay, its armature *a* completes the following circuits for the red lamp R. From the common wire 105, wire 131, armature 128^a, wire 133, relay 134 and wires 135 and 114 to the generator. This

35 40 45 now energized relay 134 attracts its armatures and the circuit from common wire 105, armature 134^b, wire 136, lamp R and wires 138 and 112 is established, a resistance 139 being provided to protect the low voltage lamps.

Therefore, when the coil 101 picks up current, the red lamp R burns in the cab.

45 50 55 60 65 Should the coil 100 pick up current, then the tube 102 would pass insufficient plate current and the relay 140 would be de-energized, and a circuit consisting of the common wire 105, wire 142, armature 140^a, wire 143, green lamp G, and wires 138 and 112, would be completed. The green lamp G therefore burns during only the interval that the locomotive is passing over the section of track in which the "clear" current is found. The red light, however, when it starts burning, keeps on burning until the coil 100 picks up "clear" current from an energized section at the exit end of some succeeding block, and this results from the circuit of its relay 134 being closed through the armature 140^a, wire 144, armature 134^a, wire 133, relay 134, wires 135, 114 and 112. But when the relay 140 becomes de-energized by reason of the coil 100 picking up current, this circuit to relay 134 is opened

and the red lamp ceases to burn. No current will pass to this red lamp until the coil 101 again picks up current.

An electro-pneumatic valve is employed to control the operation of the air brakes 70 and consists of a body 9 having a series of superimposed chambers. A magnet 160 is mounted in the upper chamber and has lead wires 161 and 162, and this magnet, when energized, draws down the armature 75 163 and the stem 164, which carries the valve 165 which normally closes the passage between the chamber 166 to which the pipe 167 connects, and the chamber 168 which has a relief passage 169. The second 80 valve 170, on this stem, normally opens the passage between the chamber 166 and the chamber 171 to which the pipe 172 connects.

The pipe 172 connects to the main air 85 reservoir and the air pressure within the chamber 171 together with the small spring 173 are sufficient to hold the valve 170 onto its seat, unless the magnet is energized to hold down this valve and the stem. The 90 pipe 167 connects to the brake control mechanism which is held in normal position, as will be described later on, by the pressure of air from the main reservoir, through pipes 172 and 167. But when the magnet 95 is de-energized, the valve 170 closes the passage between these pipes and the control air escapes through the relief passage 169.

So long as relay 128 is energized, current 100 flows to the magnet of the valve 9 over common wire 105, wire 131, armature 128^a, wire 145, forestalling key 146, and wire 162, and from the valve 9 over wires 161 and 112 to the generator. But when the coil 101 picks up current and the relay 128 is de-energized, this circuit is opened and the connection between pipes 167 and 172 is closed, which will result in the setting of the air brakes.

The length of track which carries sufficient 110 electro-magnetic flux to influence the instrumentalities on the locomotive is so limited that a train moving at ordinary speed passes over it before the circuit between two certain wires 148 and 149 is opened as herein-after explained. It will be understood that tube 102 has nothing to do but to put out lamp R and to cause current to flow to lamp G. Tube 103 controls the operation of the 115 electro-pneumatic valve.

When relay 128 is de-energized by reason of coil 101 picking up current, the circuit of this relay cannot again be closed so long as this coil functions. But as soon as current in this coil ceases, the grid of tube 103 loses 120 its effective negative bias of potential so that current may now flow from the filament to the plate of this tube. This may be secured by depressing key 146 which closes the circuit from the filament to the plate of tube 125 130.

103, to relay 128, over wire 147, key 146, wire 148, switch 36, and wires 149 and 129 to the high voltage side of the generator 104.

The stick circuit (already traced) for the 5 relay 128 is immediately closed by armature 128^b over wire 129, so that the key 146 may be released to close the circuit to the electro-pneumatic valve. But while the coil 101 is receiving current, this stick circuit cannot 10 be closed and the plate circuit cannot carry current and the electro-pneumatic valve cannot receive current so that the brakes must be applied unless the locomotive has carried this coil 101 beyond the charged zone.

15 While the mechanism hereinafter described forms no part of the present invention, a description thereof is given so that the operation of train control systems of this character may be fully understood.

20 In the ordinary air brake system installed on many of the locomotives in use in this country, two manually operated brake control valves 1 and 4 and an air operated distributing valve 3 are employed. The valve 25 1 connects to the pipe 2 which in turn connects to the train pipe 15 and its function is to release the air in this pipe 2, which results in the application of the train brakes, to admit air to this pipe from the main pressure tank which results in the release of the 30 train brakes and to control the action of the distributing valve 3 whose function is to apply and release the locomotive brakes simultaneously and proportionately to the action of the train brakes.

35 The independent valve 4 functions to admit air from the main pressure tank to the locomotive air pipe (not shown), which results in the application of the locomotive brakes, independently of the train brakes, and to release the pressure on this air pipe releases the locomotive brakes independently 40 of the train brakes, which may be desirable when a heavy train is on a down grade and the engineer wishes to save his locomotive brakes while still using his train brakes.

45 The distinction between the valves 1 and 4 is primarily that when valve 1 releases the pressure on the train pipe, the train brakes are applied, but when valve 4 releases the pressure on its air pipe, the locomotive brakes are released. On the other hand, an increase of pressure on the train pipe releases the train brakes but pressure applies the locomotive brakes. As the two valves 50 are interconnected, it is evident that leakage of train pipe pressure at the distributor valve 3 to the valve 4 may cause application of the locomotive brakes. In order to prevent this, a manually operated cock was provided to permit escape of any such pressure in the locomotive air pipe to the valve 1 and the open air, and this cock was closed when two locomotives operated together as a 55 "double-header", in which case the brakes of

one locomotive had to be under the control of the engineer of the other. This leakage during "double-heading" would be watched and released by the second engineer.

When the valve 1 was in brake-release or 70 running position and the cock was open, this leakage escaped through that valve, but when this valve was in brake-applying or "lap" position, the escape was prevented so that the locomotive brakes would be applied 75 by the action of the distributor valve 3. Theoretically, such leakage should not occur, but in actual practice it is sufficient to require the cock above mentioned.

80 In the present system, I have substituted an air operated valve 7 for the cock above mentioned for the reason that an application of the brakes because of the operation of the automatic train control system shown in the drawing may occur when the valve 1 85 is in running position, in which event no application of the locomotive brakes would result unless the by-pass provided for this leakage is closed. The open stop cock would therefore prevent the application of the locomotive brakes. The air operated valve 7, therefore, is open during normal operation 90 of the locomotive but closed during the operation of the automatic train control system.

As above explained, when the coil 101 95 picks up "danger" current, the magnet 160 becomes de-energized and the pipe 137 is connected to the relief vent 169. The spring 13 will therefore press the valve 12 against its seat 14. As soon, however, as the magnet 160 is re-energized, air under pressure 100 will flow from the pipe 172 past the valve 170 through pipe 167 to the space above the piston 10 and open the passage between the pipe 6 and the automatic valve 3. 105

The brake-control mechanism shown in cross section at the middle of the drawing embodies a valve chamber 20 with a slide valve 21 therein connected to a stem 22 which is slidable by a piston 23 in the small cylinder 24. Below this chamber 20 is a second cylinder 25 containing a piston 26 connected to a stem 27 carrying the valve 28 which normally engages a seat 29 forming part of the chamber 30. Below the chamber 30 is another cylinder 32 in which the piston 33 is slidable, being normally held up by the spring 34 on the stem 35, and this stem carries an arched electrical contact 36 normally engaging the contact blocks 37 and 37^a. The wires 148 and 149 connect to the contacts 37 and 37^a respectively. The cap 38 protects this switch.

The drawing shows the piston 23 and valve 21 just after the pressure in the outer 125 end of the cylinder 24 has been reduced because of the magnet 160 being deenergized, the valve 170 closing the passage between the pipes 167 and 172 and the small valve 165 opening the passage from the pipe 167 130

to the vent 169. This movement of the valve 21 is caused by air flowing from train pipe 15 through passages 40 and 41 and acting on a second piston 42 on the stem 22.

5 While the valve 21 was in its normal position against the shoulder at the right end of chamber 20, air under train pipe pressure flowed from the chamber 20 through the port 43 in the valve 21, through the passage 10 44 to the upper end of the cylinder 25, through the passage 45 and pipe 47 to the lower chamber of the valve body 49. From this chamber, air flows through pipe 50 to the tank 51.

15 At the same time the small valve 53 was held off its seat in the small chamber 54 at the end of the main valve chamber 20 by the valve 21, the stem of the valve 53 being loose in its support and permitting a slow flow 20 of air from this chamber 20 to the control tank 55 through pipe 56 and into the upper chamber 57 of the valve 49.

A smaller flexible diaphragm 59 and a larger flexible diaphragm 60 are mounted in 25 the valve body 49 and support the valve 62 which normally opens the vent to the pipe 63 which connects to a passage 64 opening into the space 67 below the valve 21.

When the valve 21 has reached the position shown, the spring 66 forces the small valve 53 onto its seat, preventing leakage 30 from the tank 55 which retains normal train pipe pressure. The valve 21 by means of its port 67 connects the passage 64 and pipe 35 63 to the whistle 68, and air flows from above the piston 26 and from the tank 51 through the pipe 63 to this whistle. The reduction of air pressure above the piston 26 is rendered slow by this tank 51. When 40 the downward air pressure on the piston 26 and stem 27 falls to less than the upward air pressure thereon, the piston and valve will rise and air from the train pipe will rush down into the chamber 32, depressing the piston 33 and escaping through the holes 45 70. At the same time the contacts 36 and 37 separate, opening the forestalling-key circuit.

So long, therefore, as the pressure above 50 the piston 26 is at not less than a certain percentage of the train pipe pressure, the circuit between the forestalling key and the valve 9 may be closed and the engineer may prevent the application of the brakes thereby, the circuit to the electro-pneumatic valve 9 being established as above described.

But if the engineer delays depressing his forestalling key until the air pressure above the piston 26 is sufficiently reduced to permit the air pressure below it to raise it and the valve 28, the rush of air downward opens the switch between the wires 148 and 149 and holds this switch open until the air pressure on the train line is sufficiently reduced to 60 cause an application of the air brakes, and

thereafter until the pressure above the piston 33 falls so low that it cannot prevent the spring 34 from pushing up the piston 33. Should the engineer feed air into the train pipe in an endeavor to release the brakes, 70 such added air would assist in holding the valve 28 open, but if he assists in reducing this train pipe pressure, the valve 28 will close earlier.

The upper diaphragm 59 of the valve 49 75 is always under initial train pipe air pressure. When the pressure above the piston 26 and below the diaphragm 60 has fallen so that the total pressure below the diaphragm 60 is less than the total pressure 80 above the diaphragm 59, the valve 62 closes and prevents further reduction, which results in the piston 26 forcing the valve 28 to its seat, provided, of course, the valve 1 is at "lap" position. The piston 33 is then 85 lifted by its spring 34 and the contacts 36 and 37 engage to close the forestalling-key circuit, so that the engineer can reset the relay 128 as before described.

The details of construction of this safety 90 mechanism and the proportions of its parts may all be changed by those skilled in the art without departing from the spirit of my invention as set forth in the following 95 claims.

I claim:—

1. In a system of the class described, comprising collector coils mounted on a track vehicle, adjacent the track, a current source, two electron tubes, an electric circuit between each coil and the grid of one of said tubes, and an electric circuit between the current source and the filaments of both of said tubes connecting to both of said coils. 100

2. In a system of the class described, an 105 electron tube, a current source to energize the tube, a coil adapted to be energized by current from a stationary conductor, and circuits carrying the energizing current for the tube from the current source by way of the coil to the grid of the tube and a controlling current from the coil to the tube. 110

3. In a system of the class described, an 115 electron tube, a current source to energize the tube, a coil adapted to be energized by current from a stationary conductor, circuits carrying the energizing current from the current source by way of the coil to the tube and a controlling current from the coil to the grid of the tube, and a casing enclosing 120 said coil and the adjacent portion of said circuit. 125

4. In a system of the class described, an 130 electron tube comprising a filament, plate and grid, a current source to supply filament and plate current, and circuits embodying a collector coil adapted to be energized by current from a stationary conductor, said circuits carrying current from the current source through the collector coil to the fila-

ment and plate, and a control current from the coil to the grid.

5. In a system of the class described, a plurality of electron tubes each comprising a filament, plate and grid; a current source to supply filament and plate current to said tubes; an electric circuit to carry current from the current source to the filaments and plates of said tubes comprising a plurality of collector coils adapted to be energized by currents from a stationary conductor; and independent conductors between said coils and said grids.

10. In a system of the class described, a current source, a normally energized electro-pneumatic valve to control a brake system, an electron tube, a source of current of

comparatively low tension and a source of current of higher tension, a circuit for the low tension current connecting to said valve, 20 a relay to open and close said circuit, a circuit for the higher tension current including said relay and the plate circuit of said tube, a collector circuit connected to the grid of said tube and adapted to interrupt the plate 25 current to cause said relay to be de-energized, a manually operable key normally closing the low tension circuit to said valve, and an additional higher tension circuit adapted to be closed by said key to close the 30 plate circuit to said relay to cause it to be re-energized.

JAMES E. CLARK.
